UNITED STATES PATENT OFFICE

OCTAWE LE CLAIR VALENTINE, OF BRIDGEPORT, CONNECTICUT, ASSIGNOR, BY MESNE ASSIGNMENTS, TO THE BAY COMPANY, OF BRIDGEPORT, CONNECTICUT, A CORPORATION OF DELAWARE

CONTAINER

Application filed April 5, 1927, Serial No. 181,023. Renewed December 3, 1929.

This invention relates to containers, and more particularly relates to a container for a roll of material, such as ribbon, tape, adhesive plaster, etc., from which it is expected that various lengths will be taken and used from time to time.

The principal object of this invention is to provide a container which is simple and inexpensive in construction; compact; easy and convenient to handle, both in packing the material therein and in dispensing material therefrom; one in which the roll of material may be placed without difficulty; one which does not require the trouble and expense of forming the material into a roll by hand; and a container which is sanitary, and keeps the contents free from dirt and dust.

A further object of this invention is to provide a container of the character described, from which the contents may be dispensed readily and easily.

Another object of my invention is to provide a container especially well suited for packing rolls of adhesive plaster, which container will so hold the plaster that there will be no radial pressure on the roll, and thereby will prevent such compacting of the plaster as might cause the medicament of one ply to adhere to the back of the adjacent ply, in which case a portion of the plaster would be damaged. Another object of my invention is to provide a container in which previously formed rolls of adhesive plaster may be packed, and one which permits the dispensing of adhesive plaster in a most convenient manner. Adhesive plaster is relatively heavy, and another object of my invention is to provide a container which will not come open or spill its contents at inopportune times, due to the weight of the plaster, or for other causes.

Other objects of this invention will be in part obvious and in part pointed out hereinafter.

In order that a clearer understanding of this invention may be had, attention is hereby directed to the accompanying drawings forming a part of this application and illustrating certain embodiments of this invention.

Referring to the drawings, Fig. 1 is a sectional view of a filled and closed container embodying this invention; Fig. 2 is an enlarged sectional view of a fragment of the same, with certain parts separated; Fig. 3 is a sectional view of a fragment of a closed and filled container embodying my invention in a modified form; Fig. 4 is a sectional view of a fragment of a filled container showing another modification and with certain parts separated; and Fig. 5 is a view similar to Fig. 4, but showing still another modification.

Similar reference characters refer to similar parts throughout the several views of the drawings.

Referring to the drawings, the container includes a box, comprising a body 1 and bottom 2, secured together, and a cover 3 to the center of which is secured a spindle 4 on which the roll 5 of adhesive plaster, or other material, is placed, and from which the material is dispensed. The spindle 4 is of resilient material, such as sheet metal, and may be clinched securely to the cover by means of the flanges 6 and 7, as shown, or may be secured to the cover in any suitable manner desired, as by soldering or otherwise. The spindle is split, as at 8, so that the outer or free end of the spindle may be compressed to reduce its diameter, and thus allow the core 9, on which the packed material is wound, to be passed over a bead or flange 10 formed on the end of the spindle, the diameter of the bead being normally greater than the diameter in the hole of the core, so that after the roll of material is placed on the spindle, it cannot pass the bead 10, and, therefore, cannot fall or slip from the spindle. However, the roll 5 is free to rotate on the spindle.

The free end of the spindle and the bottom of the box interengage to prevent the container from opening at inopportune times. To this end, as shown in Figs. 1 and 2, an internal, helical head or thread may be formed on the spindle near its free end, adapted to be engaged in a corresponding helical groove 12 formed in a post 13 secured to the bottom of the container, and which fits within the end of spindle 4, so that

when the cover of the box is applied, a slight turn will engage the thread 11 in its groove 12 and will securely fasten the cover and box together. When it is desired to obtain a piece of material from the roll, a slight turn of the cover or box in the proper direction will release the spindle 4 from the post 13, and the cover, with the roll, carried thereon, can be removed readily from the box.

10 The box cover provides a convenient hand grip, whereby a person can support the roll with one hand while pulling upon the free end of the material with the other hand, to unroll the desired length and remove it from the roll for use. It will be noted that since the roll of material revolves easily on the spindle, the hand grip (cover) does not rotate while the material is being unrolled, thus eliminating the inconvenience which otherwise would be occasioned, and which otherwise would be apt to result in the cover and material being dropped or pulled from one's grasp in consequence of the strong pull required to unwind the plaster from the roll.

15 20 25 By anchoring the free end of the spindle to the bottom of the box, the roll of material is held in a central position in the box, and preferably out of contact with the sides thereof. The roll cannot rest radially against the box, even when the box is on its side. The roll is always supported from its core, and, therefore, under no conditions can the roll be subjected to radial inward pressure which might cause the layers to adhere so tightly together

30 35 40 45 50 that the adhesive substance will become displaced or torn from its backing when the material is unrolled.

In view of the peculiar nature of the adhesive substance, excessive tension must be avoided when the roll is formed. By providing a container adapted to receive material previously wound on a core, the forming of the roll may be accomplished with automatic machines of a type now available on the market. If the container required the material to be wound on the spindle 4, it would not be possible to use these machines, and a great increase in expense would be involved, which expense is avoided by my improved construction.

Instead of providing the spindle 4 and post 13 with interengaging thread 11 and groove 12, the releasable interlock between the spindle 4 and box bottom 2 may be obtained, as shown in Fig. 3, by securing to the box bottom 2 a post 14, fitting about the outside of the spindle, and having a bead or shoulder 15 behind which the bead 10 on the free end of the spindle is adapted to engage. The spindle end, being diametrically resilient, permits a person to push the spindle bead 10 across the post bead 15 by exerting a slight pressure or pull, depending on whether the box is being closed or opened. The resiliency of the spindle 4 keeps the spindle bead 10 engaged with

sufficient tightness behind the post bead 15 to prevent the box cover 3, and the roll of material 5 carried thereby, from falling from the box at inopportune times.

Fig. 4 illustrates another possible form of interlock between the free end of the spindle and the box bottom. In this form the post 16 is provided with bayonet slots 17, and the bead on the free end of the spindle is replaced by lateral projections on lugs 18 which are engageable in the bayonet slots to hold the cover and box together. In this case the lugs 18 serve to retain the roll of material 5 on the spindle 4, and, as before, the fact that the spindle is diametrically compressible permits the roll of material prewound on a core 9 to be passed over the lugs 18 into place on the spindle.

Still another modification is shown in Fig. 5, wherein the extremity of the free end of the spindle and its bead 19 is in the shape of a helix so as to be engageable in a helical thread 20 formed in the post 21 secured to the bottom 2 of the box.

The posts referred to may be constructed of any suitable material and may be affixed to the box bottom in any suitable manner, for instance, by clinching the box bottom between two flanges 22 and 23, as shown in Figs. 1 and 2, or by soldering or welding as shown at 24 in Fig. 4. If the cover 3 is perforated where the spindle is attached thereto, the hole may be closed by a cap or plug 25 or in any manner desired. Similarly, if the box bottom 2 is perforated where the post is affixed thereto, a cap or plug 26 may be supplied to close this hole. The object of closing these openings is to prevent dust or dirt from entering the box and settling on the roll of material packed therein.

The cover preferably fits closely against the upper edge of the box so as to prevent dirt or dust from entering the box at this point. The cover may be flat or may be formed with a friction flange 27 which fits against the inside of the box.

Obviously many modifications of the construction are possible without departing from the scope of my invention, and it is obvious that, although my invention is particularly well suited for adhesive plaster, the container is no less suited for rolls of material other than adhesive plaster, for instance, ribbons, tapes, and strips of various materials.

Accordingly, as many changes could be made in the above construction, and as many apparently widely different embodiments of this invention could be made without departing from the scope thereof, it is understood that all matter contained in the above description or shown in the accompanying drawings be interpreted as illustrative and not in a limiting sense.

What I claim is:—

1. A container of the character described,

including a box portion having a bottom, a cover, a spindle secured at one end to the cover and extending from the cover to the box bottom when the cover is in place in the box portion, and means on the center of the box bottom engageable with the free end of the spindle, when the container is closed, for anchoring and supporting the free end of the spindle centrally in the container and for removably locking the cover to said box bottom, said spindle being adapted to carry rotatably a spool of material.

2. A container of the character described, including a box portion having a bottom, a cover, a spindle secured at one end to the cover and extending from the cover to the box bottom when the cover is in place in the box portion, and means on the center of the box bottom engageable with the free end of the spindle, when the container is closed, for anchoring and supporting the free end of the spindle centrally in the container and for removably locking the cover to said box bottom, said spindle being adapted to carry rotatably a spool of material, and means on said spindle adjacent its other end, for holding the spool of material out of contact with the cover portion.

3. In a container of the character described, a box, including a body and a bottom, and a cover therefor having a spindle adapted to be enclosed within the box when the container is closed, and means extending radially outward from the end of the spindle for confining a roll of material on the spindle, the end of the spindle being resilient and diametrically compressible, permitting the roll of material to be passed over said means into confined position on said spindle.

4. In a container of the character described, a box, including a body and a bottom, and a cover therefor having a spindle adapted to be enclosed within the box when the container is closed, and means extending radially outward from the end of the spindle for confining a roll of material on the spindle, the end of the spindle being resilient and diametrically compressible, permitting the roll of material to be passed over said means into confined position on said spindle, said spindle comprising a split tube of resilient material.

5. In a container of the character described, a box, including a body and a bottom, and a cover therefor having a spindle adapted to be enclosed within the box when the container is closed, and means extending radially outward from the end of the spindle for confining a roll of material on the spindle, the end of the spindle being resilient and diametrically compressible, permitting the roll of material to be passed over said means into confined position on said spindle, said spindle comprising a split tube of resilient material, and said means including

a bead or lugs formed on the end of the spindle.

6. In a container of the character described, a box including a body and a bottom having a post, a cover therefor having a spindle adapted to be enclosed within the box and to releasably interlock with said post when the container is closed, said spindle having means on its end for confining a roll of material on the spindle and being resiliently compressible diametrically at its end to permit the roll of material to be passed across said means into confined position on said spindle.

7. In a container of the character described, a box including a body and a bottom having a post, a cover therefor having a spindle adapted to be enclosed within the box and to releasably interlock with said post when the container is closed, said spindle having a bead on its end for confining a roll of material on the spindle and being resiliently compressible diametrically at its end to permit the roll of material to be passed across said bead into confined position on said spindle, and means on the box bottom adapted to be engaged by the spindle bead to hold the free end of the spindle centrally in the container.

8. In a container of the character described, a box including a body and a bottom having a post, a cover therefor having a spindle adapted to be enclosed within the box and to releasably interlock with said post when the container is closed, said spindle having means on its end for confining a roll of material on the spindle and being resiliently compressible diametrically at its end to permit the roll of material to be passed across said means into confined position on said spindle, the end of said spindle fitting within said post and having a bead adapted to interlock behind a bead on said post, the beads on said spindle and post having approximately the same diameters.

9. A container of the character described, including a box portion having a bottom, a cover, a spindle secured at one end to the cover and extending from the cover to the box bottom when the cover is in place in the box portion, means on the center of the box bottom engageable with the free end of the spindle when the container is closed, removably securing the cover to said box bottom, said spindle being adapted to carry rotatably a spool of material and compressible means on the free end of said spindle for removably holding the spool of material on the spindle and out of contact with the cover portion.

This specification signed this 31st day of March, 1927.

OCTAWE LE CLAIR VALENTINE.
